UNITED STATES PATENT OFFICE.

JOHN G. BOWMAN, OF KANSAS CITY, MISSOURI, ASSIGNOR OF ONE-HALF TO WILLIAM C. HASELTINE, OF KANSAS CITY, MISSOURI.

CURTAIN ROD AND SHADE STICK.

Application filed December 1, 1925. Serial No. 72,587.

The invention relates to new construction in cloth, or other web fastenings, which will at the same time serve as a curtain rod or shade stick, and provide means whereby this 5 rod may be mounted in a novel way, while the cloth is gripped therein. Additional objects, advantages and features of invention reside in the construction, arrangement and combination of parts, as may be understood 10 from the following description and accompanying drawings, wherein,

Figure 1 shows an embodiment of a curtain rod in elevation, as mounted upon a window with a curtain engaged therein;

Figure 2 is a cross section of Figure 3;

Figure 3 is an elevation of a shade stick or the like embodying my invention;

Figure 4 is a fragmentary perspective of the cover and clamp plate 90;

Figure 5 is a similar view of the rod 15.

There is illustrated a sheet metal body rod 15, the blank for which may be substantially rectangular in form, and has two opposite parallel edges recurved inwardly to form 25 opposite lip portions 16 and 17 parallel to the body of the blank a short distance, the lip 16 being somewhat longer than the lip 17. The rod thus has a channel between the lips, and these lips are spaced from the body 30 of the plate sufficiently to accommodate goods and tongue of a complementary cover plate, as will be described.

In practice, the body 15 has been made of eighteen gauge metal, the distance between 35 the lines of bending and adjacent opposite edges being from three quarters to one inch, while the length of the lip 17 has been made approximately one-eighth of an inch, and the length of the lip 16 nearly or quite one- 40 quarter of an inch.

There is shown a combined closure plate and locking plate 90 adapted to be applied to the assembly of a rod, or stick such as involved in Figures 1 and 3, a plate 90 is 45 formed very much like the rod 15, but at intervals its more extended inturned edge portions are slit and bent to form tongues 91—92, recurved outwardly and backwardly, so as to form edge portions, which may be 50 inserted under the lips 16 and 17 of the rod 15. The lips 91 are longer than the ones 92, located at the opposite edge, and after the goods is laid over the rod 15, this plate 90 is laid over the goods with the tongues 55 against the goods, the long tongues 91 being

located adjacent the long lip of the rod. The plate 90 is then pressed upon so as to force the tongues 91 and goods into the channel of the rod and the plate 90 then moved so as to slide the lips 91 under the long lip 60 16 of the rod, after which the short tongues 92 are similarly pressed against the goods so that they enter the channel of the body 15 when the plate 90 is moved transversely 65 upon the rod 15 so as to engage the tongue 92 under the short lip 17 of the rod, after the manner shown in Figure 2. The short lip of the rod and the short tongues of the plate 90 are preferably located at the lower side of the assembly when it is applied to the lower 70 edge of a curtain shade, so that the weight of the plate 90 will hold it in engaged position, in addition to the effect caused by the shade itself, which tends also to move the parts to proper engaging position after the 75 tongues are inserted in the channel and will also retain them in such position, by the weight of the combined assembly. The ends of the plate 90 may have tongues 93 formed 80 on the body portion extending from the ends and turned inwardly over the ends of the device, so as to close the open ends of the plate 90 and also the rod 15 when the parts are assembled.

In Figure 3 an ornamental shade stick 85 produced by the utilization of my invention is shown, in which the lower edge of the shade material 84 may be secured and also entirely concealed. This device embodies two sections in one of which the lower edge portion of the shade 84 is secured by the interlocking of the other.

In addition, a split sleeve 78 of short length is slid over the stick assembly, with the open side uppermost and receiving the shade 84 90 therethrough as shown in Figure 3. This sleeve is moved to a central position on the assembled shade stick. A ring 88 is engaged loosely in the sleeve at the lower side, whereby the shade may be manipulated. This rod 100 and stick assembly may of course be applied to curtains of various kinds, as well as shades, and may be employed in various situations where it is necessary to apply a rigid reinforcement of the end of a sheet of material 105 to hold it in form, or to enable it to be pulled upon and to distribute local force throughout the width of the goods.

I claim:

A curtain rod and the like comprising a 110

member of sheet metal having opposite longitudinal edges inturned to form lips in spaced relation to the body of the member, one lip being longer than the other, and a second member similar to and over the open side of the first member, and having in addition extensions from its inturned edges—a long one from the longer lip and a short one from the shorter lip, said extensions engaged re-

movably under the respective first named lips, the extreme edges of the extensions being spaced a distance corresponding to the distance from the bight of the long lip of the first named member to the extremity of the short lip of the first named member, for the purposes described.

In testimony whereof I affix my signature.
JOHN G. BOWMAN.
